UNITED STATES PATENT OFFICE

JOHN H. HELMS, OF FORTVILLE, INDIANA

GRINDING MACHINE

Application filed August 5, 1929. Serial No. 383,609.

This invention appertains to polishing and grinding and more particularly to a novel device for grinding cylinders, particularly the cylinders of triple valves used in air

5 brakes.

An important object of my invention is the provision of a novel device for truing and grinding the cylinders of triple valves embodying novel means for holding the triple 10 valve centered relative to the grinding tool, and novel means for feeding the grinding tool into the cylinder.

Another important object of my invention is the provision of means for expanding and 15 contracting the grinding tool, said means acting to uniformly expand the tool whereby the cylinders will be uniformly ground in a true circle.

A still further object of my invention is to 20 provide a grinding device for the cylinders of triple air valves of the above character, which will be durable and efficient in use, one that will be simple and easy to manufacture and one which can be placed upon the market 25 at a reasonable cost and permit the quick and expeditious grinding of the cylinders.

With these and other objects in view, the 30 invention consists in the novel construction, arrangement and formation of parts, as will be hereinafter more specifically described, claimed, and illustrated in the accompanying drawings, in which drawings:

Figure 1 is a fragmentary side elevation 35 of my improved cylinder grinder showing the same in operation, parts of the grinder and the cylinder of the triple valve being shown in vertical section;

Figure 2 is a detail section taken on the 40 line 2-2 of Figure 1 looking in the direction of the arrows illustrating the cylinder centering head and casing in top plan;

Figure 3 is a side elevation of the cylinder 45 centering head and casing in side elevation

showing parts thereof broken away and in section;

Figure 4 is a section through the head taken on the line 4-4 of Figure 3;

Figure 5 is a top plan view of the centering 50 bed for the triple valve cylinder;

Figure 6 is a detail section taken on the line 6-6 of Figure 1 looking in the direction of the arrows;

Figure 7 is a detail fragmentary side elevation 55 showing the adjusting nut and the head for the grinding tool;

Figure 8 is a detail side elevation of the grinding tool;

Figure 9 is a top plan view of the grinding 60 ring, and

Figure 10 is a top plan view of one of the expanding disks for the grinding ring.

Referring to the drawings in detail, where-in similar reference characters designate cor- 65 responding parts throughout the several views, the letter A generally indicates my im- proved grinding machine which comprises a bed or supporting plate 15 having secured thereto the upstanding pillar or post 16, the 70 upper end of which is provided with a Y- shaped head 17. This head is provided with horizontally alined bearings 18 for the re- ception of an operating shaft 19, which may be driven in any preferred way. The for- 75 ward edge of the Y-shaped head 17 supports a vertically disposed guide 20 which slidably receives the adjusting sleeve 21, one face of which is provided with a rack bar 22. This sleeve 21 has journaled therein and for slid- 80 ing movement therewith the tool shaft 23 which has feathered thereon a bevel gear 24. This bevel gear 24 meshes with a bevel gear 25 keyed or otherwise secured to the drive shaft 19. By this construction the tool shaft 85 can be raised and lowered by the sleeve 21 and the lower end of the shaft below the sleeve 21 is provided with a head 26 for con- nection with the grinder, which will be later 90 described. The sleeve 21 can be raised and 90

lowered by any suitable means such as a pinion 27 which meshes with the rack bar 22 and this pinion can be turned by a suitable hand crank 28, if desired.

5 The grinding device per se comprises a shank 30, the upper end of which has keyed or otherwise secured thereto, as at 31, a coupling head 32 which receives the head 26 on the lower end of the tool shank 23 and this 10 socket is rigidly connected to the head by the use of a suitable thumb screw or the like 33. The lower end of the shank 30 is provided with a reduced threaded extension 34 forming a shoulder 35 as can be seen by referring 15 to Figure 1 of the drawing. This shank is rotatably mounted within a bearing sleeve 36, which is in turn received in the centering head or casing 37. A suitable key and keyway 38 slidably connects the bearing sleeve 36 with the centering head 37 and thus the two 20 are united against rotary movement relative to one another, but the sleeve is permitted of sliding movement relative to said head. The upper end of this sleeve is externally threaded as at 39 for the reception of the adjusting nut 40 which can be provided with a plurality of radially extending manipulating handles 41. The outer surface of this nut is preferably calibrated as at 42 for cooperation 25 with a pointer 43 secured to the sleeve. The upper end of the nut 40 and the sleeve 36 bears against a suitable thrust bearing 44 carried in a protecting cap 45 which is keyed or otherwise secured to the shank 30 as at 46. 30 The lower end of the shank carries a similar cap 47 which bears against a thrust bearing 48. This thrust bearing 48 in turn bears against the grinding tool per se indicated by the reference character 49, which will now 35 be described.

The grinding tool per se comprises an upper tapered disk or cone 50 which is mounted directly on the shank 30 and a lower oppositely disposed tapered disk or cone 51 which 40 is mounted on the threaded extension 34 of the shank against the shoulder 35 and held thereon by a suitable nut 52. Received between the tapered disks or cones 50 and 51 is a resilient split ring 53, the outer surface 45 of which carries suitable grinding material such as emery cloth or the like for engaging and grinding the walls of the cylinder of the triple valve indicated by the reference character 54. It is obvious that when the tapered cones 50 and 51 have been brought toward one another, the split ring 53 will be uniformly expanded for bringing the same to the desired diameter and against the wall of the cylinder. Conversely when the tapered disks or cones 50 and 51 are spread apart, the split ring 53 is allowed to contract. By operating the nut 40 against the thrust bearing 44, the sleeve 36 can be slid downwardly for moving the disk 50 toward the disk 51 and when the nut 40 is threaded against the thrust

bearing, the split ring is allowed to expand. In order to insure the proper rotation of the grinding tool 49, the lower disk 51 can carry a lug 55 which fits within a notch 56 formed in the lower edge of the split ring 53.

70 The head 37 can carry a depending lug 57 which is adapted to fit within a port hole 57 formed in the cylinder 54, so as to hold the head stationary on the cylinder and to center the cylinder relative thereto.

75 In order to effectively hold the cylinder 54 on the bed plate 15 and to properly center the same relative to the shank 30 I provide a novel holder or bed. This holder 58 is provided with a plurality of upstanding pins 80 59 which engage in openings 60 already formed in the cylinder 54. The plate 58 can be adjusted on the bed plate 15 by screws 61 which are threaded into brackets 62 mounted at appropriate points on the bed 85 plate 15.

80 From the foregoing it is obvious that the grinding tool can be raised and lowered into the cylinder by means of the pinion 27 and the rack 22 and that the tool can be expanded or contracted by the nut 40. The shank can be rotated at the desired rate of speed by driving the shaft 19 at the required revolutions.

90 The head 37 is provided with openings 64 to allow the escape of the brass removed from the cylinders. The sleeve 36 can be provided with a suitable oil way 65 leading from the upper cap 45 for the thrust bearing 44 so that the lower thrust bearing can be lubricated.

95 From the foregoing description it can be seen that I have provided an exceptionally simple and novel grinding device which will expeditiously and effectively grind the cylinders of triple valves true and accurately.

100 Changes in details may be made without departing from the spirit or the scope of this invention, but

110 What I claim as new is:

115 1. A cylinder grinder comprising a bed, a post on said bed, bearings on the post, a rotatable shaft carried by the bearings, means for rotating the shaft, a tool shaft slidably and rotatably carried by the post, means for rotating the tool shaft from the drive shaft, means for raising and lowering the tool shaft, a tool shank, means for coupling the tool shank to the tool shaft, means for anchoring a cylinder to be ground to the bed, a centering head for engaging the upper end of the cylinder, a bearing sleeve slidably carried by said centering head, the shank being rotatably mounted in the sleeve, a bearing cap on the shank, an adjusting nut threaded on the sleeve, a thrust bearing interposed between the adjusting nut and cap, a reduced extension on the lower end of the shank, a grinding tool including a lower disk fitted 120 on said reduced extension having its upper 125 130

face tapered inwardly, an upper disk having its lower face tapered inwardly mounted on said shank, a split contracting ring mounted between said disks and engaging the tapered faces thereof, and a thrust bearing interposed between the upper disk and said sleeve.

2. In a cylinder grinding machine, a bed, a tool shank rotatably and slidably mounted above the bed, a holding plate, means for adjusting the plate on the bed, centering pins carried by the holding plate for receiving a cylinder, a sleeve slidable on the shank, a centering head slidable on the sleeve having a pin for engaging the cylinder to be ground, and a grinding tool carried by the lower end of the shank.

In testimony whereof I affix my signature.
JOHN H. HELMS.
